UNITED STATES PATENT OFFICE

2,541,846

REINFORCED BOX

Fred J. Ullrich, Kalamazoo, and Lee A. Forden,
Detroit, Mich.

Application June 19, 1947, Serial No. 755,570

7 Claims. (Cl. 217—69)

1

This invention relates to improvements in reinforced boxes.

The main objects of this invention are:

First, to provide a stacking and nesting box in which the bottom and side and end walls may be formed of relatively light or thin panel stock, at the same time are so supported that a strong rigid structure capable of carrying heavy loads results and one which is capable of withstanding very severe usage.

Second, to provide a box having these advantages in which the portions ordinarily subject to blows and impacts in use are effectively reinforced and one in which there are no exposed sharp edges.

Third, to provide a structure having these advantages in which the parts may be economically produced and easily assembled and shipped in the knockdown if desired and set up or erected by relatively inexperienced mechanics.

Objects relating to details and economies of the invention will appear from the description to follow. The invention is defined and pointed out in the claims.

A preferred embodiment of the invention is illustrated in the accompanying drawing, in which:

Fig. 1 is a perspective view of a box embodying the invention with the stacking bails in erected position.

Fig. 2 is a fragmentary exploded view illustrating certain structural details of the parts.

Fig. 3 is an enlarged fragmentary view on a line corresponding to line 3—3 of Fig. 4.

Fig. 4 is an inverted fragmentary outside perspective view of one corner of the box.

Fig. 5 is a fragmentary vertical perspective view of a box looking from the inside and prior to the attachment of the runners.

Fig. 6 is a fragmentary perspective view illustrating the structure and the manner of assembling one of the corner uprights with the end horizontal member.

In the accompanying drawings the invention has been illustrated as embodied in a stacking and nesting box. Certain features, however, are desirable for use in non-stacking box structures and in non-nesting structures having vertical walls.

It will be understood that in the specification and claims the terms "sides" and "ends" are used for convenience in description and designating the parts although the invention may be embodied in receptacles or boxes of square shape.

The embodiment of the invention illustrated

2

comprises a bottom 1, side walls 2, 2 and end walls 3, 3, these being preferably of thin panel stock. They may be of fiberboard or of veneer material. One of the advantages of the invention is that relatively thin bottom and wall stock may be used.

The side horizontal members 4 are of angle section disposed facing upwardly and inwardly. They may be formed of sheet metal of suitable gauge. The bottom legs 5 are secured to the bottom by the fasteners 6, desirably by rivets when the box is permanently assembled.

The side walls 2 are secured to the vertical legs of the side horizontal members by the fasteners 7. The vertical legs 4 of the side horizontal members are cut away at 8 for a purpose which will appear as the description proceeds. The end horizontal members 9 are also of angle section and are disposed facing upwardly and inwardly and are provided with angularly disposed arms 10 at the ends thereof. The horizontal legs of the end members have angular slot-like openings 11 at the corners thereof.

The end walls are secured to the vertical legs 25 of the horizontal end members by fasteners 7 conventionally illustrated. It will be understood that the legs of these horizontal members are provided with holes 12 to receive the fastenings 7.

The horizontal legs of the end horizontal member arms are lapped upon the horizontal legs of the side members and secured thereto, the vertical legs being secured to the side walls by fasteners 7.

The vertical legs of the side horizontal members are cut away at the ends so that the vertical legs of the arms may lie close against the side walls.

The angled corner uprights 13 are lapped upon the adjacent ends of the side and end walls and are provided with holes 14 receiving the fasteners 7. These fasteners are shown conventionally with the exception of the enlarged views of Figs. 3 and 4. These corner uprights are disposed through the slot-like openings 11 in the end horizontal members and they are provided at their lower ends with runner supporting foot portions designated generally by the numeral 15, these foot portions of the runner supports being formed by folding the bottom portions 16 and 17 of the legs of the corner uprights into superimposed relation as clearly shown in Figs. 4, 5 and 6.

These foot portions have holes 18 therein adapted to receive the rivets 19 which are arranged through the runners 20 arranged on the 55 foot portions as is clearly shown in Figs. 2 and 3.

These runners have reduced end portions 21 engaging the supports. The runners are arranged below the horizontal legs of the angled horizontal side members and secured thereto as by the fasteners 22.

The side and end rim members 23 and 24 are arranged on the outer sides of the wall panels and secured thereto as by the rivets indicated at 25. The ends of these rim members overlap the corner uprights.

Top corner irons 26 are provided, these being angled to embrace the ends of the side and end rim members and are preferably provided with top and bottom flanges 27 and 28 which engage the tops and bottom edges of the rim members.

The pintle bearings 29 are arranged through openings 30 formed in the arms of the corner irons, there being outward offsets 31 surrounding the openings to receive the retaining flanges 32 of the bearing members.

The stacking bails or irons 33 are provided with arms 34 having inturned bearing engaging pintles 35 at the ends thereof so that the stacking irons or bails are pivotally supported to swing across the top of the box as shown in Fig. 1 or to depend at the end of the box. When in erected position they engage the top flanges of the corner irons. This distributes the load on the stacking irons to the side and end rim members and the supporting walls and the corner irons also serve as wear members protecting the walls and rim members. By arranging the corner uprights through the horizontal connecting and reinforcing members the load and stresses are well distributed and also projecting vertical edges at the corner eliminated at the point where they would be likely to engage in handling and dragging the box on its runners.

Structures embodying the invention are very strong and rigid in proportion to the weight of the stock employed and are capable of carrying heavy loads. The invention has been illustrated and described in a highly practical embodiment thereof. Certain other embodiments and adaptations have not been illustrated or described which are contemplated as it is believed that this disclosure will enable those skilled in the art to embody or adapt the invention as may be desired.

Having thus described our invention, what we claim as new and desire to secure by Letters Patent, is:

1. In a box, the combination of a bottom and side and end walls, angled horizontal side members disposed facing upwardly and inwardly on the outer sides of the bottom and side walls and secured thereto, angled horizontal end members disposed facing upwardly and inwardly on the outer sides of the bottom and end walls and secured thereto and to said angled side members, the end horizontal members having angular openings therethrough adjacent the ends thereof at the corners of the box, inwardly facing angled corner uprights arranged through said openings and on the outer sides of the side and end walls and secured thereto, the angle of said angular openings corresponding to that of the angular corner members to facilitate a fitting engagement of the corner members within the openings, the lower ends of the flanges of said corner uprights providing runner supports, runners disposed with their ends above and secured to the said runner supports of said corner uprights, rim members secured on the outer sides of the side and end walls, and angled top corner irons

secured upon the adjacent ends of the rim members.

2. In a box, the combination of a bottom and side and end walls, angled horizontal side members disposed facing upwardly and inwardly on the outer sides of the bottom and side walls and secured thereto, angled horizontal end members disposed facing upwardly and inwardly on the outer sides of the bottom and end walls and secured thereto, the end horizontal members having angularly disposed arm portions at their ends secured to the bottom and side walls and the bottom legs of the side horizontal members, the horizontal legs of the end horizontal members having angular slot-like openings therethrough at the corners thereof, inwardly facing angled corner uprights arranged through said openings and on the outer sides of the side and end walls and secured thereto, the lower ends of the flanges of said corner uprights being turned inwardly into overlapping relation providing runner supports, runners disposed on and secured to the horizontal legs of said side horizontal members with their ends above and secured to the said runner supports of said corner uprights, rim members secured on the outer sides of the side and end walls overlapping said corner uprights, and angled top corner irons secured upon the adjacent ends of the rim members.

3. In a box, the combination of a bottom and side and end walls, angled horizontal side members disposed facing upwardly and inwardly on the outer sides of the bottom and side walls and secured thereto, the vertical legs of the horizontal side members terminating in spaced relation to the horizontal legs thereof, angled horizontal end members disposed facing upwardly and inwardly on the outer sides of the bottom and end walls and secured thereto, the end horizontal members having angularly disposed arm portions at their ends secured to the bottom and side walls and the bottom legs of the side horizontal members, the horizontal legs of the end horizontal members having angular slot-like openings therethrough at the corners thereof, inwardly facing angled corner uprights arranged through said openings and on the outer sides of the side and end walls and secured thereto, the lower ends of the flanges of said corner uprights being turned inwardly into overlapping relation providing runner supports, and runners disposed on and secured to the horizontal legs of said side horizontal members with their ends above and secured to said runner supports of said corner uprights.

4. In a box, the combination of a bottom and side and end walls, angled horizontal side members disposed facing upwardly and inwardly on the outer sides of the bottom and side walls and secured thereto, angled horizontal end members disposed facing upwardly and inwardly on the outer sides of the bottom and end walls and secured thereto, the end horizontal members having angular openings therethrough adjacent the ends thereof at the corners of the box, inwardly facing angled corner uprights arranged through said openings and on the outer sides of the side and end walls and secured thereto, the angle of said angular openings corresponding to that of the angular corner members to facilitate a fitting engagement of the corner members within the openings, the lower ends of the flanges of said corner uprights providing runner supports, rim members secured on the outer sides of the side and end walls, and angled top corner irons and runners disposed with their ends above and

secured to the said runner supports of said corner uprights.

5. In a box, the combination of a bottom and side and end walls, angled horizontal side members disposed facing upwardly and inwardly on the outer sides of the bottom and side walls and secured thereto, angled horizontal end members disposed facing upwardly and inwardly on the outer sides of the bottom and end walls and secured thereto, the end horizontal members having angularly disposed arm portions at their ends secured to the side horizontal members, the horizontal legs of the end horizontal members having openings therethrough at the corners thereof, inwardly facing angled corner uprights having runner supporting foot portions at their lower ends arranged through said openings and on the outer sides of the side and end walls and secured thereto, runners disposed on and secured to the horizontal legs of said side horizontal members with their ends above and secured to the said foot portions of said corner uprights, rim members disposed on the outer sides of the side and end walls.

6. In a box, the combination of a bottom and side and end walls, angled horizontal side members disposed facing upwardly and inwardly on the outer sides of the bottom and side walls and secured thereto, angled horizontal end members disposed facing upwardly and inwardly on the outer sides of the bottom and end walls and secured thereto, the end horizontal members having angularly disposed arm portions at their ends secured to the side horizontal members, the horizontal legs of the end horizontal members having openings therethrough at the corner thereof, inwardly facing angled corner uprights having runner supporting foot portions at their lower ends arranged through said openings and on the outer sides of the side and end walls and secured thereto, and runners disposed on and secured to the horizontal legs of said side hori-

zontal members with their ends above and secured to the said foot portions of said corner uprights.

7. In a box, the combination of a bottom and side and end walls, angled horizontal side members disposed facing upwardly and inwardly on the outer sides of the bottom and side walls and secured thereto, angled horizontal end members disposed facing upwardly and inwardly on the outer sides of the bottom and end walls and secured thereto, the end horizontal members having angularly disposed arm portions at their ends, the horizontal legs of the end horizontal members having openings therethrough, inwardly facing angled corner uprights having runner supporting foot portions at their lower ends arranged through said openings and on the outer sides of the side and end walls and secured thereto, and runners disposed on and secured to the horizontal legs of said side horizontal members with their ends above and secured to the said foot portions of said corner uprights.
